Primary Examiner — Kimberly Barnes

(57) **CLAIM**

The ornamental design for a ribboned fedora motorcycle helmet, as shown and described.

DESCRIPTION

FIG. 1 is a perspective view of a ribboned fedora motorcycle helmet of the present invention.

FIG. 2 is a top view of the ribboned fedora motorcycle helmet of the present invention.

FIG. 3 is a bottom view of the ribboned fedora motorcycle helmet of the present invention.

FIG. 4 is a side view of the ribboned fedora motorcycle helmet of the present invention.

FIG. 5 is another side view of the ribboned fedora motorcycle helmet of the present invention.

FIG. 6 is a front view of the ribboned fedora motorcycle helmet of the present invention; and,

FIG. 7 is back view of the ribboned fedora motorcycle helmet of the present invention.

The broken lines in the drawings depict portions of the ribboned fedora motorcycle helmet that form no part of the claimed design.

1 Claim, 5 Drawing Sheets
